UNITED STATES PATENT OFFICE

SHERWOOD T. MOORE, OF ORANGE, NEW JERSEY, ASSIGNOR TO THOMAS A. EDISON, INCORPORATED, OF WEST ORANGE, NEW JERSEY, A CORPORATION OF NEW JERSEY

PRODUCTION OF PHONOGRAPH STYLI

Application filed January 22, 1929. Serial No. 334,152.

My invention relates to the production of phonograph styli and particularly to the production of such styli as are designed to track and reproduce so-called "hill and dale" records wherein the undulations corresponding to the sound waves are formed on the bottom of the record grooves, and where the grooves of such records are very minute, that is, of extremely small depth and width.

In a well-known make of disc phonograph record of the "hill and dale" type, the record groove has a pitch of $1/150''$, that is, the record disc has 150 threads per radial inch, the bottom of the groove in transverse cross-section has the form of a circular arc and the groove has a maximum depth of about $.0017''$ and a maximum width of about $.0066''$, the grooves in the master of such a record being cut by a style with a circular cutting edge which has a diameter of $.008''$. The stylus employed for tracking and reproducing such a record is made from a suitable piece of very hard long-wearing material, preferably diamond, and comprises a cone-shaped portion having a rounded end designed properly to fit freely in and track the record groove, such tracking end usually being formed as part of a sphere having a diameter of $.0075''$. The spherical tracking end portion of such a stylus is formed by a grinding operation, usually carried on in an automatic grinding machine, wherein the pointed end of the conical portion of the stylus is maintained in engagement with a flat surface of a rotating lap charged with diamond dust, while the stylus is at the same time rotated about its axis and also oscillated about the point where it engages the lap.

In the case of a "hill and dale" record of the character described but in which the record groove has a pitch materially less than $1/150''$ the maximum depth and width of the groove are necessarily considerably less than in the case of a 150 thread record and it is also necessary in order to obtain a groove of sufficient depth to permit proper tracking thereof by a reproducing stylus, that the bottom of the groove in transverse cross-section be formed on a circular arc of smaller diameter. For example, in the case of a "hill and dale"

record of this character having 450 threads to the radial inch, the maximum depth of the record groove is about $.0005''$, the maximum width thereof is about $.002''$ and the groove in the masters of such records is cut with a style having a circular cutting edge which is about $.003''$ in diameter. It is impracticable, however, to employ for tracking and reproducing records having such extremely minute grooves, the usual form of stylus having a rounded or spherical tracking end portion of such size as properly to fit the grooves, for such a spherical tracking portion would of necessity be formed on such a small radius as to be the equivalent of a point and would in fact be so sharp that in tracking the record groove it would cut into and gouge the record to such an extent as to soon render the record useless. Moreover, such spherical tracking end portions of conical-shaped styli of diamond or the like designed for use with a minute record groove of the form just referred to, are of such small dimensions that attempts to form the same by the usual grinding operations above described invariably result in the breakage of such end portions.

The principal objects of my invention are to provide a new, improved and practicable method for producing phonograph styli with tracking end portions adapted to fit very minute record grooves of the character referred to, and which are of such form that they will not cut into the material of the records in tracking the grooves thereof; and to provide improved apparatus for effectively carrying out such method.

Generally described, my improved method consists in grinding the tracking end portion of a stylus to form by effecting tracking movement of the stylus in the groove of a grooved lap formed of or charged with abrasive material and simultaneously effecting relative rocking movement of the lap and stylus preferably in the direction of said groove. The groove of the lap is preferably spiral and such tracking movement of the stylus in said groove is preferably effected by rotating the lap while the stylus is maintained in engagement with the groove and the relative rocking move-

ment of the stylus and lap during the tracking of the groove of the lap by the stylus is preferably substantially uniform in extent and rate and is preferably effected by rocking the stylus.

Other objects and features of my invention will be hereinafter more specifically described and claimed.

In order that my invention may be more clearly understood attention is directed to the drawings accompanying and forming a part of this specification and in which:

Figure 1 is a plan view of a preferred form of my improved apparatus;

Fig. 2 is a view in side elevation looking from the right in Fig. 1;

Fig. 3 is an enlarged detailed view in side elevation of the stylus supporting means of the machine shown in Figs. 1 and 2 and of parts associated therewith;

Fig. 4 is a diagrammatic plan view illustrating the feeding movement partaken of by a stylus being formed by the use of the machine shown in Figs. 1 to 3 in tracking a grooved lap actuated by such machine, the stylus being shown in the position it occupies in an outer and an inner convolution of such groove (the other convolutions of the groove being omitted) and with its tracking portion shown in horizontal cross-section in substantially the ultimate desired form thereof, the stylus and also the inner and outer convolutions of the groove of the lap being greatly exaggerated in size;

Fig. 5 is a view similar to Fig. 4 but with that portion of the inner convolution of the groove of the lap shown in Fig. 4 as engaged by the stylus, superimposed on the corresponding portion of the outer convolution of such groove;

Fig. 6 is a greatly enlarged view in side elevation, partly broken away, of a stylus provided with a tracking portion produced in accordance with my invention, looking toward one side of such tracking portion;

Fig. 7 is a view similar to Fig. 6 but looking toward an end of the tracking portion of the stylus;

Fig. 8 is an enlarged fragmental sectional view of the grinding lap taken transversely of the groove therein, showing a stylus engaging such groove;

Fig. 9 is a view similar to Fig. 8 of a record with which a stylus having a tracking portion formed in accordance with my invention is designed to be used and showing the tracking portion of such a stylus in engagement with the groove of the record, the dimensions of the record groove, however, being shown on a larger scale than the groove of the lap shown in Fig. 8; and

Fig. 10 is a view similar to Fig. 9, the section, however, being taken lengthwise of the record groove.

The apparatus illustrated in Figs. 1 to 3

for carrying out my improved method comprises a substantially rectangular casing 1 on which is rotatably mounted a turntable 2 for carrying a lap A, said turntable being applied to the upper end of a vertical shaft 3 which is journaled in a suitable bearing 4 with which the top of the casing is provided. An arm 5 comprising a supporting means for stylus the tracking end portions of which are to be formed by the machine, is mounted for swinging movement about a fixed axis and also for movement in the direction of such axis by being secured to a rod 6 which is rotatably and slidably mounted in spaced vertically aligned bearings 7 and 8 with which the top and front wall of the casing 1 are provided. The arm 5 comprises a lower horizontal portion extending rearwardly from the rod 6 within the casing 1, a vertical portion 5' extending upwardly within the casing from said horizontal portion and through an opening 9 in the top of the casing, and a horizontal upper end portion 5'' extending forwardly from the vertical portion 5'. An attachment 10 is removably secured to the upper end of arm 5, by the turntable collar 10', the construction and arrangement being such that when said arm is swung about its pivotal axis the attachment 10 will be moved over and across the turntable 2. The attachment 10 is similar to a well-known form of phonograph reproducer for playing "hill and dale" records except that the usual flexible diaphragm of the reproducer cup is replaced by a stiff metal disc 11. This attachment comprises a member in the form of a floating weight 13 which carries a stylus lever and which is connected to the cup wherein disc 11 is mounted for lateral and vertical movements relatively to the cup, by means of the pivotal and spring mounting 14, such movements of said weight being limited by the coaction of a pin 15 secured to the weight with a loop or stirrup 16 secured to the cup and into which said pin extends. The stylus lever 17 is removably mounted at 18 on the weight 13 for pivotal movement about a horizontal axis, said lever having a stylus B to be formed secured in one end thereof and having its other end flexibly connected with the disc 11 by a link preferably in the form of a cord 19, which extends through a suitable opening provided in said weight.

A horizontal shaft 21 is mounted in suitable fixed bearings provided on the rear wall of the casing 1 adjacent the top of the latter, and is adapted to be driven by an electric motor or other suitable source of power as by means of a pulley 22 secured to the shaft and a belt 23 passing over said pulley. The shaft 21 also has three additional pulleys 24, 25 and 26 secured thereto. A pulley 27 is secured to the turntable shaft 3 and the latter and thereby the turntable 2 are adapted to be driven from the shaft 21 by a belt 28 passing over

the pulleys 24 and 27 and two intermediate idler pulleys 29.

Suitable automatic feeding means is provided for swinging the arm 5 about its pivotal axis to thereby move the attachment 10 across the turntable 2 and the disc-shaped lap A removably mounted on the turntable. As shown, this automatic feeding means comprises a segmental rack 30 formed on one end 10 of an arm 31 which is pivotally mounted at 32 adjacent its other end on a bracket 33 secured to the rod 6, and a worm 34 with which the rack 30 normally engages. The worm 34 is secured to a horizontal shaft 35 which is 15 journaled in fixed bearings 36 and has one end extending outwardly through a side wall of the casing 1. A spring 37 fixed at one end to the arm 5 and at its other end to the arm 31 at a point intermediate the rack 30 and the 20 pivot 32, tends to hold the rack 30 always in engagement with the worm 34. The shaft 35 and the worm 34 carried thereby are driven from the shaft 21 by a belt 38 which passes over the pulley 25 on the shaft 21 and a second pulley 39 secured to the outer end of said shaft.

The vertical position of the support or arm 5 and of the stylus carrying attachment 10 is controllable by suitable manually operable means, such as the cam 40 which is 30 pivotally mounted at 41 on the upper end portion of the rod 6 above the bearing 7 and is provided with an operating handle 42. When the said handle is moved to the dotted 35 line position shown in Fig. 3, the cam 40 coacts with the upper surface of bearing 7 to move the rod 6 and thereby the arm 5 and attachment 10 upwardly to a raised inoperative position, in which movement the 40 floating weight 13 will be raised by engagement of the bottom of loop 16 with pin 15 and thereby lift the stylus B from engagement with the lap A. When the arm 5 and rod 6 are thus raised, the spring 37 will of 45 course act to hold the rack 30 in engagement with worm 34. I provide suitable means, however, whereby the rack 30 may readily be raised from engagement with worm 34 against the action of spring 37 so 50 as to permit the arm 5, when in said raised inoperative position, to be swung about its pivotal axis and the stylus B brought to any desired position over the lap A. This means as shown consists of a stirrup 44 pivotally 55 mounted on a collar 45 fixed to the rod 6, such stirrup having an arm 46 extending outwardly and upwardly through an opening in the front wall of casing 1 and also having rearwardly extending curved leg portions 47 60 in the ends of which is fixed a pin 48 arranged to coact with the end portion 31' of the rack arm 31. The handle or arm 46 is located adjacent the handle 42 of cam 40 so that it may readily be engaged and moved by a 65 finger of the hand of the operator used in

moving said cam. When thus moved to the dotted line position shown in Fig. 3, the stirrup 44 will of course be moved about its pivot and the pin 48 will coact with the end portion 31' of the rack arm 31 to move the latter to the dotted line position shown with the rack 30 disengaged from the worm 34.

When the handle 42 is raised to vertical position, rod 6 and arm 5 and of course the parts carried by the same, move under the action of gravity to their lowered operative position, as shown in full lines in Fig. 3, and are supported in such position by an eccentric or cylindrical cam 49 which is disposed a suitable distance below the pivoted end of the arm 5; the said cam being fixed to a horizontal shaft 50 which is journaled in spaced bearings 51 provided on the casing 1 and which extends outwardly through one side wall of the casing. A pulley 52 is applied to the outer end of shaft 50, and the latter and cam 49 are adapted to be driven from the shaft 21 by a belt 53 which passes over the pulleys 26 and 52. I preferably provide suitable means whereby rod 6 and arm 5 and the parts carried thereby, when in lowered operative position, are adjustably supported by the cam 49. As shown this means comprises an arm or member 55 pivotally connected at one end to a bracket 56 on the arm 5 and disposed between the latter and the cam, a spring 57 which is connected at its ends to the arm 5 and member 55 and which constantly tends to move the latter towards said arm, and a screw 58 which is threaded through a lug 59 provided on arm 5 and which when turned coacts with member 55 at its free end to adjust the position thereof with respect to arm 5.

The construction and arrangement are 103 such that when the arm 5 and rod 6 are lowered to operative position in which they are supported by the cam or eccentric 49 (through the engagement of the latter by member 55), cam 40 will be spaced somewhat 110 above bearing 7 whatever the angular position of the eccentric, and weight 13, by reason of the engagement of stylus B with lap A, will be moved upwardly to a position in which pin 15 is raised from engagement with the bottom of loop 16, all as shown in full lines in Fig. 3. If the eccentric 49 is now rotated this will obviously effect vertical reciprocatory movement of arm 5 and thereby 115 similar movement of the relatively fixed parts of attachment 10 towards and away from lap A. During such rectilinear reciprocatory movement of arm 5 and the relatively fixed parts of attachment 10, the said parts will, because of the connection 14, move vertically with respect to the floating weight 13, which will then act to maintain the stylus B in engagement with lap A; and at the same time, because of the flexible connection 19 120 between stylus lever 17 and plate 11, a slight 125

vertical rocking movement will be imparted to said lever and stylus, about the pivot 18. The limits of the rocking movement so imparted to the stylus and stylus lever are indicated in full and dotted lines in Fig. 3. The arrangement is also preferably such that the rocking movement imparted to the stylus B will be substantially in the direction of any portion of the groove of lap A with which the stylus may be engaged. In the reciprocatory movements of arm 5 and the relatively fixed parts of attachment 10 effected by rotation of cam 49 when said arm and parts are in their operative positions, the bottom of loop 16 should never engage pin 15 as this would result in disengaging stylus B from lap A and also interrupt the desired rocking movement of the stylus; and this result may be ensured in any case by properly adjusting the member 55 with respect to arm 5 by means of screw 58. This adjustable feature is important as different laps which may be used with the machine, as well as the styli to be formed and the levers for such styli, will vary somewhat in their dimensions. For a given speed of rotation of the driving shaft 21, it is apparent that the reciprocatory movement of arm 5 and the rocking movement of stylus lever 17 resulting from the rotation of cam 49 as above described, will each be at a uniform rate. The extent of these movements will also be uniform—and while of course dependent, in part at least, on the eccentricity of cam 49, is preferably small; the extent of the reciprocatory movement of arm 5 being represented by the distance between the horizontal lower portion thereof and the dotted line X and the limits of the rocking movement of stylus lever 17 being indicated by the full and dotted line positions thereof (Fig. 3).

The lap A is preferably in the form of a metal disc or plate having a spiral groove G therein and charged with a suitable finely divided abrasive material, preferably diamond dust. To facilitate the application of the diamond dust to the lap, the same is mixed with a suitable carrier, preferably either olive oil or machine oil. The pitch of groove G is of little importance except that it should be such that a stylus tracking the groove will be fed thereby across the lap at the same rate at which the arm 5 and attachment 10 are moved transversely of the turntable 2, in the operation of the machine, by the feeding means comprising rack 30 and worm 34. For forming the tracking portions of styli designed for reproducing "hill and dale" records such as hereinbefore described and having 450 threads per radial inch, I prefer to use a lap A in which the groove G has a pitch of $1/150''$, a uniform width of approximately $.003''$, and a uniform depth of approximately $.0015''$ and is substantially semi-circular in transverse cross-section. It

will be noted that the groove G is about three times as deep and about one-half again as wide as the groove of such a 450 thread record at the points in the latter of maximum depth and width, although the bottoms of both such grooves in transverse section, are formed on circular arcs of the same radius. The groove G of lap A, as shown in the drawings, is supposed to represent a spiral groove of the pitch, shape and dimensions just described. It is to be understood, of course, that in each case the form and dimensions of the groove of the lap will be dependent, in part at least, on the form and maximum depth and width of the grooves of the records with which the styli to be formed are designed to be used.

In forming the tracking portion of a stylus B having a conical-shaped portion C, in accordance with my invention and with the apparatus described, the procedure is preferably as follows: The stylus B is preferably permanently mounted in one end of a stylus lever 17, which is to eventually constitute a part of the reproducer of a phonograph, with its conical portion C projecting from the lever. The lever 17 is then pivotally mounted at 18 on the floating weight 13 of attachment 10 and connected to the disc 11 of the latter by the flexible cord or link 19, and said attachment is secured in proper position on the free end of arm 5 by the collar 10. The arm 5 is brought to a position corresponding to that shown in full lines in Fig. 1, in which the stylus B will be directly above the outer convolution G' of the groove in lap A and is then lowered to operative position, by moving the cam 40 to the full line position shown in Fig. 3, to engage the pointed end of stylus B with such outer convolution, while the rack 30 is at the same time permitted to engage worm 34. Assuming that the shaft 21 is being rotated at constant speed, which is the case in the normal operation of the machine, the arm 5 will now be slowly moved about the axis of rod 6 to the dotted line position thereof shown in Fig. 1 and cause the end of the stylus to track the groove G of the rotating lap A to the inner convolution G² thereof, while at the same time vertical rocking movement uniform in extent and rate and substantially in the direction of the groove, will be imparted to the stylus. The arm and attachment 10 are then raised to inoperative position, corresponding to the uppermost dotted line positions thereof shown in Fig. 3, by moving the handle 42 to horizontal position, to thereby disengage the stylus from the lap; and rack 30 is disengaged from worm 34 by actuating the yoke or stirrup 44 through handle 46 thereof. The operations just described are repeated to cause the stylus to retrack the groove G or any selected portion or portions thereof as many times as may be necessary to grind the tracking end

portion of the stylus to the desired form. Usually it is found that the tracking portion of the stylus will be ground to the desired form after being fed across the lap or portions thereof from four to twelve times.

The tracking portion of the stylus produced in the manner described above, designated by reference character T in Figs. 4 to 10, is in the form of a narrow elongated shouldered shoe or runner the long dimension of which is in the direction of the groove of the lap. Referring to Figs. 4 and 5, in which D represents the axis of rod 6 about which the stylus B moves in tracking the groove G of lap A, and EE represents the arc on which said stylus moves in tracking said groove from the outer convolution G' to the inner convolution G² thereof, it will be seen that the angular position of the stylus with respect to said groove constantly changes as the stylus moves towards the inner convolution. Because of this the end portions of the tracking shoe or runner T will be ground narrower than the central portion thereof, and such central portion itself will be ground somewhat narrower than the width of groove G. Accordingly the shoe or tracking portion T as finally formed, will fit freely without binding, in both the inner and outer convolutions G' and G², as well as all intermediate convolutions. This is well illustrated in Fig. 5, wherein the inner convolution G² of the groove in the lap is represented, by dotted lines, in the position it would occupy if moved about the axis D in fixed relation to a radius from axis D to arc EE, until the portion thereof shown in Fig. 4 as engaged by shoe T is superimposed on the corresponding portion of the outer convolution G'. The ends 40 of the shoe consist of portions of the surface of the cone C into which the surfaces of the sides of the shoe smoothly merge. The bottom of the runner or shoe T, in the direction of its length, is formed on a fairly flat arc, 45 due to the slight rocking movement imparted to the stylus as it tracks the groove of the lap A; but the radius of said arc is such that the toe and heel at the ends of the said bottom of the shoe T will, when the latter is tracking a 50 450 thread record, clear all portions of the bottom of the record groove. To illustrate this, a stylus B having such a shoe or runner T is shown in Fig. 10 as tracking a portion of the groove K of a 450 thread record R which represents sound waves of substantially the highest frequency which are ever 55 phonographically recorded, or in other words a portion of such a groove in which the "hills" and "dales" are the steepest which 60 occur.

While the contour of the sides and bottom of the shoe T, at any transverse cross-section of the latter, is substantially a smooth curve, it is not circular, for the upper portions 65 of the shoe during the forming thereof

in the manner described, are ground to a thickness somewhat less than the width of the upper portions of the groove G of lap A. Accordingly, when tracking the groove of a 450 thread record of the character described, 70 said shoe will generally ride on the bottom of such groove and clear the top side edges thereof. This is illustrated in Fig. 9 which shows the shoe T engaging the groove K of a 450 thread record R, said figure being a sectional view of a fragment of the record taken transversely of such a groove where it is of substantially maximum depth.

The shoe or tracking portion T of a stylus formed as described will wear away the side walls of the curved record grooves but very slowly, for in tracking such grooves it will have an extended bearing thereon as compared with the usual forms of stylus heretofore employed.

When the operations necessary for forming the tracking portion of a stylus have been completed in the apparatus described, the stylus lever 17 in which the stylus is fixed may be removed from the apparatus for assembly in a reproducer, and replaced by a like lever having mounted therein another stylus to be formed with such a tracking portion.

It is to be understood that the apparatus and method herein shown and specifically described are subjected to many changes and modifications without departing from the spirit of my invention or the scope of the appended claims.

Having now described my invention what I claim and desire to protect by Letters Patent, is as follows:

1. Apparatus of the character described comprising a rotatably mounted spirally grooved lap, means for rotating said lap, a stylus support, said lap and support being arranged for relative feeding movement to cause a stylus carried by the support to track the groove of the lap when the latter is rotated, and means for effecting relative rocking movement of said lap and stylus as the latter tracks said groove, substantially as described.

2. Apparatus of the character described comprising a rotatably mounted spirally grooved lap, means for rotating said lap, a stylus support, said lap and support being arranged for relative feeding movement to cause a stylus carried by the support to track the groove of the lap when the latter is rotated, and means for effecting rocking movement of said stylus substantially in the direction of said groove while tracking the latter, substantially as described.

3. Apparatus of the character described comprising a rotatably mounted spirally grooved lap, a stylus support adapted and arranged to be fed transversely of said lap when the latter is rotated to thereby cause a stylus carried by the support to track the

groove of the lap, and means for effecting rocking movement of said stylus substantially in the direction of said groove while tracking the latter, substantially as described.

4. In apparatus of the character described, a rotatably mounted spirally grooved lap, means for rotating the same, a support mounted for feeding movement across said lap and also for movement in a direction towards and away from the same, means for imparting such feeding movement to said support when said lap is rotated, a lever mounted on a pivot movable with respect to said support, said lever carrying a stylus at one end and having its other end flexibly connected to said support, and means for effecting movement of said support in a direction towards and away from said lap during the feeding movement thereof, substantially as described.

5. In apparatus of the character described, a spirally grooved disc lap mounted for rotation about a fixed axis, means for rotating said lap, a support pivotally mounted for swinging movement across said lap about an axis parallel to the axis of the lap, means for imparting such swinging movement to said support when said lap is rotated, said support being also movable in the direction of the axis of its pivotal mounting, a lever mounted on a horizontal pivot which is movable with respect to said support, said lever carrying a stylus at one end and being flexibly connected at its other end to said support, and means comprising a rotatable eccentric cam adapted when said lap is rotated to effect reciprocatory movement of said support in the direction of the axis of its pivotal mounting, substantially as described.

6. In apparatus of the character described, a turntable rotatable about a given axis, a support mounted for movement towards and away from said turntable, a member connected with said support for movement relative thereto, a stylus carrying lever pivoted on said member and flexibly connected at one end with said support, an eccentric adapted when rotated to cooperate with said support and effect movement of the latter towards and away from said turntable, and means for rotating said eccentric when the turntable is rotated, substantially as described.

7. In apparatus of the character described, a turntable rotatable about a vertical axis, a member mounted for vertical movement towards and away from said turntable, a floating weight connected with said member, a stylus carrying lever pivoted on said weight and having one end thereof flexibly connected with said member, a rotatable cam for supporting said member when the latter is in normal operative relation to said turntable, means for rotating said cam when the turntable is rotated, and a device adjustable

with respect to and whereby said member is adapted to be supported by said cam, substantially as described.

8. In apparatus of the character described, a turntable rotatable about a vertical axis, a member mounted for swinging movement about a vertical axis across said turntable and also for movement in the direction of its said axis, means for imparting such swinging movement to said member when said turntable is rotated, a floating weight connected to said member, a stylus lever pivoted on said weight and having one end flexibly connected to said member, a rotatable cam supporting said member when the latter is in normal operative relation to said turntable, and means for rotating said cam when the turntable is rotated, substantially as described.

9. In apparatus of the character described, a turntable rotatable about a vertical axis, a member mounted for swinging movement about a vertical axis across said turntable and also for movement in the direction of its said axis, means for effecting such swinging movement of said member when the turntable is rotated, a floating weight connected to said member, a stylus lever pivoted on said weight and flexibly connected at one end to said member, a rotatable cam for supporting said member when the latter is in normal operative relation to said turntable, a device adjustably mounted on said member and adapted to bear on said cam, and means for rotating said cam when the turntable is rotated, substantially as described.

10. In apparatus of the character described, a lap support rotatable about a vertical axis, a member mounted for swinging movement about a vertical axis across said support and also for movement in the direction of said axis, a floating weight connected to said member for limited relative movement, a stylus lever pivoted on said weight and having a flexible connection at one end with said member, a cam rotatable about a fixed axis and adapted to support said member when the latter is in a lowered position in which said stylus lever will be in operative relation to said lap support, means for rotating said cam when said lap support is rotated to thereby effect a limited up and down movement of said member, means for imparting swinging movement to said member when the lap support is rotated comprising a feeding element movably mounted on such member and biased to operative position, means for raising said member and thereby said stylus lever to inoperative positions with respect to said cam and lap support respectively comprising a manually operable device, and another manually operable device for moving said feeding device to inoperative position, said devices being located adjacent each other so as to be readily operable by the hand of an operator, substantially as described.

11. In apparatus of the character described, a lap support rotatable about a fixed axis, a member mounted for swinging movement about a vertical axis and also for vertical movement towards and away from said support, a floating weight connected to said member for limited relative movement, a stylus lever pivoted on said weight and having a flexible connection at one end with said member, a rotatable cam adapted to support said member in the lowered position thereof in which said stylus lever will be in operative relation to said support, means for rotating said cam when said support is rotated to thereby effect limited movement of said member towards and away from said support, feeding means for imparting swinging movement to said member when said support is rotated, and means for moving said member and thereby said stylus lever to raised inoperative positions with respect to said cam and lap support respectively, substantially as described.

12. In apparatus of the character described, a spirally grooved disc lap mounted for rotation about a given axis, driving means for rotating said lap, a support carrying a stylus and mounted for swinging movement across said lap about an axis substantially parallel to the axis of said lap to cause the stylus to traverse said lap in tracking engagement with the groove therein, means for imparting such swinging movement to said support when said lap is rotated, and means actuatable by said driving means and coacting with said support for effecting rocking movement of said stylus back and forth substantially in the direction of said groove while tracking the latter, substantially as described.

13. In apparatus of the character described, a spirally grooved disc lap mounted for rotation about a vertical axis, driving means for rotating said lap, a stylus support adapted and arranged to be fed across said lap when the latter is rotated to thereby cause a stylus carried by the support to track the groove of the lap, and means actuatable by said driving means and coacting with said support for effecting a substantially vertical rocking movement of said stylus substantially in the direction of said groove while tracking the latter, substantially as described.

14. This specification signed this 8th day of January, 1929.

SHERWOOD T. MOORE.
